(57) **CLAIM**

The ornamental design for an oral irrigator as shown and described.

DESCRIPTION

FIG. 1 is a perspective view of an oral irrigator showing the new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the figures are for the purpose of illustrating portions of the oral irrigator and form no part of the claimed design.
